UNITED STATES PATENT OFFICE.

GEORGE STEVENSON, OF CAMDEN, NEW JERSEY.

DRYING DEVICE.

1,399,903.

Specification of Letters Patent. Patented Dec. 13, 1921.

Application filed July 22, 1920. Serial No. 398,125.

To all whom it may concern:

Be it known that I, GEORGE STEVENSON, a subject of the King of Great Britain, residing at Camden, in the county of Camden and State of New Jersey, have invented 5 certain new and useful Improvements in Drying Devices, of which the following is a specification.

One object of my invention is to provide 10 an improved drying device which can be used with advantage in connection with printing presses for the purpose of quickly drying the paper and printed matter.

Another object is to make my improved 15 drying device of a durable and comparatively simple construction which can be readily put in operative position.

A further object is to so construct a device 20 of my invention that while it uses gas flames for drying purposes, the flames will not set the paper on fire even though the paper accidentally stops while over the device.

These objects, and other advantageous 25 ends which will be described hereinafter, I attain in the following manner, reference being had to the accompanying drawings in which—

Figure 1 is a top plan view of a device 30 constructed in accordance with my invention,

Fig. 2 is a cross section taken on the line 2—2 of Fig. 1,

Fig. 3 is a section taken on the line 3—3 of Fig. 1,

Fig. 4 is a fragmentary elevation of Fig. 1,

Fig. 5 is a fragmentary elevation of the device with the wire screen or gauze removed, and

Fig. 6 is a top plan view of Fig. 5.

Referring to the drawings, 7 represents 40 a gas burner including an elongated pipe 8 which has a row of holes 9 arranged in the direction of the length of the pipe and operative to permit the escape of gas to pro-

duce the flames 10 so that the flames 10 are 45 projected laterally or in substantially horizontal directions. The burner 7 is preferably of the Bunsen type which admits air with the gas so that the gas will burn with 50 a blue flame in order to prevent carbon deposit, such for example as the flame commonly used in gas ranges for cooking purposes or the like.

A frame 11 includes a strip 12 preferably 55 of metal which extends parallel with the pipe 8 as shown in Fig. 6 and to this strip

is secured at spaced distances apart a number of yoked or U-shape brace members 13; said brace members having their free ends 14 abutting the pipe 8 as clearly shown in 60 Fig. 2. Clamping bands 15 which are of substantially elliptical shape as shown in Fig. 3 clamp the strip 11 to the pipe 8 and thereby serve to hold the frame in position in connection with the pipe with the strip 65 12 opposed to the holes 9 in the pipe 8. A wire screen or gauze 16 surrounds the frame 11 and pipe 8 and the opposite edges of the screen are secured together by bolts 17 as shown in Figs. 2 and 3. 70

The clamping bands 15 preferably surround the wire screen 16 and the brace members 13 serve to hold the screen 16 in shape. Any suitable means can be employed for supporting the burner and the device can be 75 secured in such position as to extend transversely under the paper as it passes out of the printing machine; said paper being indicated at 18 in Fig. 2. The paper 18 will pass in contact with the top of the screen 80 or gauze 16 and the heat from the flames 10 will serve to dry the printed matter on the paper as the printed paper passes over the device. In addition to drying the ink on the paper the device also serves to remove 85 the static electricity from the paper; thus enabling the printed sheets to be piled in proper form which cannot be done if the paper contains electricity, as often occurs during the printing operation. 90

By arranging the parts so that the gauze or screen is of substantially elliptical or elongated cross section a comparatively long or large flame can be used and housed within the casing provided by the screen. 95

In actual practice over an extended period I have found that with the use of my device even though the paper accidentally stops while resting upon the gauze or screen 16 that the paper will not catch on fire. It will 100 become charred but it will not ignite. Furthermore an extended heating surface is provided by the screen having the shape as above described so that the paper even though run at a comparatively great speed 105 will be dried when passing over the device.

The frame 11 serves as a rigid support and serves to hold the screen in the desired form and at the same time the screen prevents the leg portions of the brace members from spreading and by drawing up upon the bolts 17 the end portions of the braces 110

serve to move outwardly and thus prevent any slack, dents or other irregularities from occurring in the gauze.

To remove the device from the pipe 8 it is merely necessary to remove the clamping bands and loosen the bolts 17 and the entire device can then be slid from the pipe and an ordinary pipe can be used in connection with the device owing to the fact that no other connecting projections are necessary in order to secure the device in proper operative position.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

25 1. A device of the character described for use in connection with printing presses for printing sheet material, including a burner pipe having a row of holes in its side to cause flames to be projected laterally therefrom in a direction substantially parallel to the printed sheet; and a screen extending laterally substantially parallel on its top with the flames and printed sheet and forming a housing for said flames; substantially 30 as described.

35 2. A device of the character described including a burner pipe having holes in its side whereby flames will be projected later-

ally; a frame having parts engaging said pipe and extending laterally therefrom; and 40 a wire screen surrounding said frame and pipe and forming a housing for said flames; substantially as described.

3. A device of the character described including a burner pipe having holes in its 45 side whereby flames will be projected laterally; a frame having parts engaging said pipe and extending laterally therefrom; a wire screen surrounding said frame and pipe and forming a housing for said flames, said 50 frame having yoked braces with their ends in engagement with said pipe; and means for drawing said screen taut around said frame whereby the frame is held to the pipe and forms a brace for the screen; substantially as described.

4. A device of the character described including a burner pipe having holes in its side whereby flames will be projected laterally; a frame having parts engaging said 60 pipe and extending laterally therefrom; a wire screen surrounding said frame and pipe and forming a housing for said flames, said frame having yoked braces with their ends in engagement with said pipe; and a strip 65 connecting said braces at points remote from said pipe whereby the frame is held to the pipe and forms a brace for the screen; substantially as described.

In testimony whereof I have signed my 70 name to this specification in the presence of two subscribing witnesses.

GEORGE STEVENSON.
